UNITED STATES PATENT OFFICE.

JACOB H. GENTER, OF NEWBURGH, NEW YORK; HELEN C. GENTER EXECUTRIX OF SAID
JACOB H. GENTER, DECEASED.

FILM-REWINDER.

1,313,084.

Specification of Letters Patent. Patented Aug. 12, 1919.

Application filed April 19, 1916. Serial No. 92,332.

To all whom it may concern:

Be it known that I, JACOB H. GENTER, a citizen of the United States, residing at Newburgh, in the county of Orange and State of New York, have invented certain new and useful Improvements in Film-Rewinders, of which the following is a specification.

This invention relates to improvements in film rewinders and its leading object is to provide a film rewinder with improved tensioning and wiping means, and an extensible reel supporting arm coöperating with the tensioning means.

Another object of the invention is the provision of a self balancing film tensioning device arranged to wipe opposite sides of the film during its travel from one reel to the other.

A still further object of the invention is the provision of a film rewinder with an improved wiper and means for detachably securing to the drum of the wiper an absorbent fabric, as felt.

A still further object of the invention is the provision of an improved frame for the film rewinder.

With the above and other objects in view the invention relates to certain useful combinations, constructions and arrangements of parts, clearly described in the following specification and fully illustrated in the accompanying drawings, in which:

Figure 1 is a side elevation showing my improved film rewinder.

Fig. 2 is a detail sectional view taken on line 2—2 of Fig. 1.

Fig. 2^a is a detail view, partly in section, of the film wiping and tensioning device.

Fig. 3 is a detail view showing a portion of the frame with the parts which are bent to form container shelves.

Fig. 4 is an enlarged sectional view taken on line 4—4 of Fig. 1.

Fig. 5 is an enlarged sectional view of a portion of the film winding machine.

Fig. 6 is a detail sectional view through one of the wiper drums used in the preferred form shown in Figs. 1 and 2.

Fig. 7 is a transverse sectional view of a modified form of wiping and tensioning drum.

Fig. 8 is a fragmentary view of the frame provided with a modified wiping and tensioning mechanism.

Referring to the accompanying drawings illustrating the practical embodiment of my invention 5 designates the main frame, which is formed on its lower edge portion with an inset bracket flange 5^a, which is adapted to seat on the upper edge portion of a table or other support and be secured thereto. The lower pendant portion of the frame 5 is provided with holes 5^b whereby it may be secured to the side edge portion of the table or support, as will be readily understood.

The upper portion of the frame 5 is provided with horizontal oppositely extending arms 7^a and 7^b which are formed with inset horizontally disposed and vertically spaced flanges 6 and 7, which are disposed in parallelism to each other. The flanges 6 and 7 and the body of the frame adjacent thereto and lying between the flanges 7^a and 7^b form guides for the extensible arms 8 and 9, which are slidably supported between said flanges and against said frame 5. The frame 5 is also formed with horizontally disposed slots 10 and 11 through which the shanks of the wing screws 12 extend.

The inner ends of the screws 12 are threaded in the nuts 13, which are fixed to the inner end portions of the extensible reel supporting arms 8 and 9, and the outer ends of said screws are formed with heads 12^a, which are adapted to bear against the outer face of the frame 5 when the screws

are tightened to clamp the arms to the frame 5 against sliding.

The arm 8 is provided on its end portion with an upper bearing 14, through which 5 the reel supporting shaft 15 is journaled, and on the end of this shaft a small pinion gear 16 is fixed. The pinion gear 16 is engaged by the internal gear teeth 17^a of the internal gear 17, which is fixed to the shaft 18, which is journaled in the lower bearing 19 formed on the end portion of the arm 8. The body of the internal gear 17 forms a shield or case to cover the small gear and the internal gear teeth meshing therewith, 10 and is provided with a suitable handle 20, whereby it may be operated. The reel supporting shaft is inclined upwardly and outwardly of the arm 8, so that the reel will slide by gravity toward the small gear 16, 15 and said shaft 15 is also provided with a suitable key 15^a, whereby the reel may be keyed thereto.

The arm 9 is provided with a terminal bearing 21 in which the shaft 22 is journaled, on which shaft the feed reel is mounted and keyed, as will be understood. One end of the shaft 21 has a circular brake element 21^a which is engaged by the brake 23, the body of which is formed of spring 25 metal, and one end of which is secured to the arm 9, so that the opposite free end will bear against the shaft 21 and retard its rotation. The tension of the brake 23 is varied by means of the screw 24, which is 30 threaded on the projection 24^a fixed to the arm 9.

On the end portion of the arm 7^b of the frame 5 the bearing 26 is provided, and through this bearing the pin or shaft 27 is 40 extended. On one end of the pin or shaft 27 the bar 28 is pivotally supported. The bar 28 is equipped with wiper and tensioning members 29 and 30, which are spaced from each other a slight distance on opposite sides of the pin or shaft 27. The members 29 and 30 are secured to the end portions of the bar 28 by means of screws or pins 31. Each member consists of a drum 32, the body of which is formed with a longitudinally disposed slot 32^a and over this body the felt or absorbent fabric material 33 is arranged. The free ends of the felt or fabric 33 are inserted in the slot 32^a and a holding bar 34 is forced into said slot between the inserted free ends of the fabric to retain the fabric stretched around the drum 32.

The bar 28 is adapted to oscillate under the stress of the film during its travel from 60 the feed reel to the take-up reel, and to limit this oscillating action a squared stop head 27^a is formed on the outer end of the shaft or pin 27. This head is normally out of engagement with the drums 32, but is adapted

to be engaged by the drums or the felt thereon, when either of said drums reaches the limit of its rocking motion, due to the oscillation of the bar. 65

The frame 5 is made of sheet metal, suitably stamped and pressed into shape, and the standard 5^x thereof is formed with outwardly forced supporting shelves 5^m and 5ⁿ, each of which is formed with integral upstanding receptacle gripping prongs or arms 5°. Two of said shelves are provided to 70 support directly under the central portion of the frame, different containers, each being provided with suitable cement or adhesive material.

The film is passed between the wiping 80 and tensioning drums, over one drum and under the other, so that both sides of the film are simultaneously wiped during its travel from the feed reel to the take-up reel. As the elevation of the film wound on 85 each reel varies the bar and its wiping and tensioning drums will be automatically oscillated, to vary the tension on the film, and the pressure exerted on one drum will be automatically transmitted to the other drum, 90 thus providing an automatic tension balancing action. By varying the extension of the reel supporting arms 8 and 9 the tension exerted by the wiping members upon 95 the film may be regulated.

In Figs. 7 and 8 I show a modified construction of the film wiper and tensioning device, and the means for detachably securing the felt to the wiping drum. In these figures 5^w designates the frame, which is 100 provided with a fixed bearing 40, located near the terminal portion of the arm 9^x. A bar 41 is rockingly supported on the bearing 40 by the pin 42, which projects through said bar 41 at a point substantially midway 105 of its opposite ends. The pin 42 may be provided with a wiping and film tensioning member or roller 43. On the opposite ends of the support in bar 41 the film wiping and tensioning members or drums 44 and 45 110 are arranged.

As shown in Fig. 7, each of the film tensioning and wiping members includes a cylindrical support 46^a carried by the bar 41. On the cylindrical support 46^a the metal 115 drum or wall 46 is mounted, and the edges 47^a and 47^b of this metal drum are spaced slightly from each other and deflected slightly inward, or rounded, so as to provide yieldable gripping jaws. The periphery of the cylindrical support 46^a is longitudinally cut-away under the deflected yielding gripping jaws or edges 47^a and 47^b, 120 as indicated at 48. Over the metal drum or wall 46 the wiping fabric or material 49 is 125 stretched, the side edge portions 49' of which are deflected inwardly toward the axis of the roller, over the deflected yielding gripping

jaws 47^a and 47^b. These gripping jaws project toward each other to grip the side faces of the locking rod or member 50, the base or underside of which is formed with oppositely inclined or beveled faces 50', and the sides of which are formed with longitudinal grooves 50^a. The end supports 46 are formed with inclined faces 46' adapted to be engaged by the inclined faces 50' of the locking bar 50, and said inclined faces 46' are spaced from the gripping jaws 47^a and 47^b to permit said jaws to yield inwardly. The edges of the wiping fabric are shown extended inwardly past the edges of the gripping jaws 47^a and 47^b, so that the said edges of the wiping fabric or material will be forced by said yielding gripping jaws into the grooves 50^a and be therein retained against accidental displacement. Owing to the angle of deflection of the free edges of the drum the gripping jaws formed thereby coöperate with the locking bar 50 to stretch the fabric when said bar is disposed on the edges of the fabric and pressed inwardly between the yielding gripping jaws.

Having described my invention, I claim and desire to secure by Letters Patent:—

1. A film rewinder having a main frame, film tensioning means on the frame, and a film reel supporting arm adjustable on the frame relative to the tensioning means.

2. A film rewinder having a main frame, a film tensioning means on the frame, comprising a centrally pivoted frame, and film engaging members secured thereto on opposite sides of said pivot, for engaging opposite sides of the film, and a reel supporting arm adjustable on said frame toward and from said tensioning means.

3. A film rewinder consisting of a main frame formed with lateral guide flanges and a slot located between said flanges and disposed horizontally on the frame, a reel supporting arm adjustable on said guide flanges, said flanges being located one above the other and the lower flange forming a seat for the arm, and a screw threaded into the arm through the slot and providing means for clamping the arm against the main frame.

4. A film rewinder having a main frame provided with horizontally disposed parallel supporting flanges, supporting arms each having portions adjustably supported between said flanges, a reel support carried by each of said arms, and means for securing said arms rigidly to said frame in their adjusted positions, and a film tensioning device secured to said frame, whereby each of said reel supports may be independently adjusted with respect to said tensioning device.

5. A film rewinder having a main frame, a pair of reel supporting devices secured thereto, one of said reel supporting devices being provided with means for effecting a

travel of the film from one reel supporting device to the other, and a film tensioning device located between said film supporting devices, and comprising a rocking frame supported on a central pivotal connection, and a pair of film engaging members secured to said rocking frame, on opposite sides of the said pivotal connection, for engaging opposite faces of the film.

6. A film rewinder having a main frame, a pair of reel supporting devices secured thereto, one of said reel supporting devices being provided with means for effecting a travel of the film from one reel supporting device to the other, and a film tensioning device located between said film supporting devices, and comprising a rocking frame supported on a central pivotal connection, and a pair of film engaging members secured to said rocking frame, on opposite sides of the said pivotal connection, for engaging opposite faces of the film, and a spring engaging said rocking frame, and holding it yielding in a predetermined position upon its central pivotal connection.

7. A film rewinder having a main frame, a pair of reel supporting devices secured thereto, one of said reel supporting devices being provided with means for effecting a travel of the film from one reel supporting device to the other, and a film tensioning device located between said film supporting devices, and comprising a rocking frame supported on a central pivotal connection, and a pair of film engaging members secured to said rocking frame, on opposite sides of the said pivotal connection, for engaging opposite faces of the film, and means for adjusting said reel supporting devices toward and from said film tensioning device.

8. A film rewinder having a main frame, a pair of horizontal film roll supporting arms projecting from said main frame in opposite directions, and adjustable horizontally with respect to said main frame, and a film tensioning device comprising a rocking frame mounted on a pivotal support secured to the main frame, and engaging said rocking frame centrally, a pair of film engaging members secured to said rocking frame on opposite sides of its central pivotal connection, for engaging opposite faces of the film, a film roll support carried by each of said adjustable arms, and means operatively connected with one of said film roll supports for effecting a travel of the film from one of said film roll supports to the other.

9. A film rewinder having a main frame provided with horizontally disposed flanges projecting from one face of the frame, supporting arms having a guiding and supporting engagement between said flanges, and being horizontally adjustable therein, and extending in opposite directions from the main frame, means for clamping said arms

to the main frame in different adjusted positions, a film roll support carried by each of said arms, means operatively connected with one of said film roll supports for effecting the travel of the film, and a film tensioning device, secured to the main frame, independently of said arms, and comprising a centrally pivoted rocking frame, a pair of film engaging members secured to said rock-

ing frame on opposite sides of its central pivot, and a spring interposed between said rocking frame and said main frame.

In testimony whereof I affix my signature.

JACOB H. GENTER.
